UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

Application filed April 20, 1928. Serial No. 271,450.

This invention relates to typographical machines, such as linotype machines of the general organization represented in Letters Patent No. 436,532 to O. Mergenthaler, 5 wherein circulating matrices are released from a magazine in the order in which their characters are to appear in print and then assembled in line, the composed line transferred to the face of a mold, the mold filled 10 with molten metal to form a slug or linotype against the matrices which produce the type characters thereon, and the matrices thereafter elevated and returned through distributing mechanism to the magazine from 15 which they started. More particularly, it relates to machines equipped with a plurality of magazines containing matrices of different fonts and arranged in constant operative relation to a corresponding plurality 20 of distributors so that distribution of the matrices into all the magazines may be carried on simultaneously. In some of the commercial machines of this class, the magazines are movably mounted so that any 25 selected one thereof may be brought into operative relation to a single or common set of assembling devices without disturbing their operative relation to the distributing mechanism, and such distributing mechanism 30 generally comprises an upper primary distributor which first sorts the matrices according to font and a plurality of lower main distributors which thereafter separate them according to character (see, for instance, my prior Patent No. 1,386,786).

The present invention is directed to a machine of the same type except that it does away with the necessity of using a special upper primary distributor for the sorting of 40 fonts and permits the use, instead, of a font separator of the kind found in the older linotype models and disclosed, for example, in the patents to Rogers, Nos. 767,169 and 799,943. In other words, the machine has 45 been designed so that the main character distributors may be arranged one above the other in superposed relation and the matrices, after casting, shifted horizontally from the second elevator into a distributor 50 box and fed therefrom directly to the screws of the upper distributor, the separation of the respective fonts being effected by a selecting bridge which supports the matrices belonging to the upper magazine until they 55 engage the upper distributor bar but which

permits those belonging to the lower magazine to clear the upper distributor and drop into a chute leading to the lower distributor. The exact manner in which this has been accomplished will best be understood from 60 the detailed description to follow.

Referring to the drawings:

Fig. 1 is a side elevation of a linotype machine embodying the present improvements;

Fig. 2 is a rear elevation of the receiving end of the distributing mechanism; and

Fig. 3 is a vertical section taken on the line 3—3 of Fig. 2.

The matrices X are stored according to 70 font in the superposed inclined magazines A, only two of which are herein shown but of which a greater number might be employed if desired. These magazines (of full length and standard form) are supported upon the 75 customary base frames A¹, conjointly constituting a shift-frame which, as later to be described, is arranged to be swung upwardly and downwardly in the machine to locate either magazine in operative relation 80 to the fixed assembler entrance or raceway B. Each magazine is provided with escape- 85 ments C which control the release of the matrices therefrom and are adapted to be actuated by a series of pivoted levers C¹ when the magazines are in operative position, the levers C¹ being operated in the usual way from the keyboard mechanism, not shown, through a corresponding series of vertical reeds C². After assemblage and 90 casting, the matrices are carried upward and delivered to the distributing mechanism which first assorts them according to font and then releases them according to character 95 so that they may be returned through one or the other magazine entrances D, D¹ to the magazine from which they started. These entrances are pivoted at their lower ends to the respective base frames A¹, as at D² and D³, and are arranged with their 100 upper ends in operative relation to the two main distributors, E, E¹, each comprising as usual a toothed distributor bar to release the matrices at different points according to character, and a distinct set of conveying 105 screws for propelling the matrices along the bar.

As best shown in Fig. 3, the two distributors are arranged one above the other with the lower distributor bar in a vertical plane 110

passing through the axes of rotation of the two front conveying screws of the upper distributor and with the rear screw of the lower distributor located in a vertical plane 5 passing through the upper distributor bar. This arrangement of the distributors differs from that shown in my own prior patent as well as the two Rogers patents before referred to, and is intended to provide for the 10 movement of the magazines in the manner next to be described, as well as the mounting of the magazine entrances later to be described.

It is important that the relation between 15 the entrances and distributors be undisturbed during the shifting of the magazines for interchange so that the distribution of matrices may be carried on continuously in the manner required. Consequently, (see 20 Figs. 1 and 3) the magazines are mounted to swing about independent axes A², A³ located immediately below the corresponding distributors E, E¹, the upper and lower base frames, respectively, being hinged at these 25 points through the medium of rearwardly extending side arms A⁴, A⁵ fastened to the upper ends thereof. In this connection, it may be observed (Fig. 1) that the magazines are closely spaced so that the movement required to locate either of them in operative 30 relation to the assembler throat B is correspondingly small. Near its lower end, the upper magazine base frame A¹ is provided on its opposite sides with a depending gage 35 piece or spacing block A⁶ which rests directly upon the lower base frame and, while thus preserving the close spaced relation of the magazines, permits the latter to partake of a slight longitudinal movement 40 relatively to each other when swung together about their respective axes A², A³.

The means herein employed for swinging the magazines consists essentially of a toggle system which is adapted to raise the shift 45 frame as it is extended and to lower it as it is collapsed. In its lowermost position, the shift frame is supported upon a pair of set screws A⁷ (Fig. 1) mounted in the framework and which are adjustable to locate the upper magazine in operative relation to the assembler throat B. In its raised position, the shift frame is supported directly by the toggle system which is so designed that, when straightened out, it will locate the 50 lower magazine in correct registration with the throat B. The toggle system, see Fig. 1, comprises two pairs of links F, F¹ intermediate connected by a transverse rod F² to which the lower members F¹ are fastened 55 and on which the upper members F are loosely mounted. The members F¹ are pivoted at their lower ends to fixed brackets O, and the members F at their free ends are formed with open bearings or forks f wherein 60 gage pins a which project inwardly from

lugs A⁸ depending from the lower magazine base frame A¹. The rod F² is limited in its movements in both directions and when rocked upwardly is stopped just past "dead center" so as to lock the magazines 70 in their raised position. The movement of the rod F² is controlled by a pivoted hand lever F³, whose longer arm extends forwardly within reach of the operator and whose shorter arm F⁴, is connected to the rod F², the arrangement being such that, when the lever is depressed, the rod F² will be rocked forwardly to extend the toggle member and, when raised, will shift 75 the rod rearwardly to collapse the toggles. The shift frame is thus swung upwardly and downwardly to definite positions to bring one or the other of the magazines into 80 operation, as desired.

In the present instance, a line of matrices to be distributed is transferred horizontally from the second elevator (not shown) into the distributor box G (Fig. 2), from which the matrices are lifted, one after the other, by the reciprocating finger G¹ above the arresting shoulders G² formed on the box rails G³ and into engagement with the conveying screws of the upper distributor E. As shown in Fig. 3, the lifting finger G¹ is operated by an offset lever g' which is actuated in the usual way from one of the upper distributor screws. As the matrices are advanced by the screws, they are momentarily supported at one level upon the rails G³ but are adapted, unless otherwise supported, to drop to a slightly lower level upon the horizontal rail sections G⁴, the latter for that purpose being recessed or cut away beyond the shoulders G². A font-selecting bridge or detector G⁵ of the usual type, arranged directly beneath the recessed portions of the rails G³, is provided to support matrices belonging to one font until they become engaged by the upper distributor bar but to permit those of other fonts to seek said lower level and thus escape the bar. Matrices to be handled by the upper distributor may therefore be plain or solid at their bottom edges so as to receive support from the bridge G⁵ (or, if notched, have their notches located out of register with the transverse ribs g of the bridge), while those intended for the lower distributor E¹ should be notched to correspond with the location of the transverse ribs g of the bridge (see Fig. 3). The notched matrices fall astride the ribs g and are advanced by the upper distributor screws across the rail sections G⁴ which drop them into a chute H leading to the lower distributor box J. This box is arranged at the entrance to the lower distributor E¹ and is substantially the same as that shown and described in my prior Patent, No. 1,563,750, to which reference may be had for more detailed information, if desired.

It will be observed (see Fig. 3) that the two distributors E and E¹ are slightly offset from vertical alinement with each other and that the chute H is shaped to correspond, such arrangement being desirable since it permits a close relation to be established between the distributors and therefore materially reduces the height of the machine. As a result of such arrangement, however, matrices dropping from the rail sections G⁴ must be immediately controlled and guided as they pass into the chute H. The guiding means employed for this purpose consists of an auxiliary deflector plate H¹ hinged at the top above the distributor E, and having its lower edge flush with the rear side wall of the chute H. Adjacent the rail section G⁴, the plate H¹ is provided with a lateral extension H² for guiding the matrices facewise, and the inner face of the plate is inclined to conform with the forward slope of the chute H. A spring latch H³, mounted in the plate H¹ and engaging an adjacent bearing bracket, is provided to lock the plate in its active position and to permit its release so that it may be swung upwardly out of the way when access to the parts is desired.

Matrices passing through the chute H enter the box J at the top and are conducted downwardly therethrough by means of the inclined guiding rails J¹ which deposits them in upright position on horizontal rail portions J² directly in the path of a horizontally reciprocating pusher member J³. The rails J¹ are formed with matrix arresting shoulders J⁴ rising from the horizontal portions J², and are provided with the customary rail extensions J⁵ arranged below the receiving end of the distributor E¹. Besides the pusher member J³, the box is also equipped with a matrix lifting finger J⁶, both of said parts being actuated from a cam shaft J⁷ driven by one of the distributor screw spindles so as to operate in perfect synchronism in feeding the matrices to the distributor. The arrangement is such that matrices reaching the horizontal rail portions J² are delivered by the pusher J³ squarely against the arresting shoulders J⁴, and from this position they are lifted by the finger J⁶ into the threads of the conveying screws which advance them along the upper edges of the extensions J⁵ into engagement with the lower distributor bar.

As shown clearly in both Figs. 1 and 3, the entrance D¹ for the upper magazine is connected to the lower distributor E¹ while the entrance D for the lower magazine is connected to the upper distributor E, it being noted that the entrance D is shaped to allow the matrices dropping from the upper distributor to fall vertically into its upper end and then carry them downwardly and rearwardly past the lower distributor

and finally forwardly at a downward inclination to deliver them straight into the upper end of the lower magazine. This particular arrangement has been resorted to in order to give access to the parts from the rear of the machine with the required facility. As thus arranged, both entrances may be swung about their respective pivotal axes D², D³ to and from operative position without disturbing any of the parts with which they are associated, the magazine entrance D, when lowered, being out of the way of the entrance D¹ so that the latter may be swung through the same path for access to the upper magazine and distributor E¹. By way of contrast, it may be stated that ordinarily the upper magazine entrance is connected to the upper distributor and the lower magazine entrance to the lower distributor (see the Rogers patents before referred to), but such an arrangement would obviously be unsuitable in the present machine.

Having thus described my invention, its construction and mode of operation, what I claim and desire to secure by Letters Patent of the United States, is as follows:

1. In a typographical machine, the combination of a plurality of main character distributors arranged at different levels and each comprising a toothed bar and a distinct set of matrix conveying screws, a font separator arranged in line with the upper distributor, a plurality of superposed inclined magazines, one for each distributor, each magazine being mounted to turn about a separate independent pivotal axis located immediately below the corresponding distributor, and means for swinging the magazines about their respective pivotal axes to bring one or another into operative position without disturbing their connection with the distributors.

2. In a typographical machine, the combination of a plurality of main character distributors arranged at different levels and each comprising a toothed bar and a distinct set of matrix conveying screws, a font separator arranged in line with the upper distributor, a plurality of superposed inclined magazines, one for each distributor, separate base frames carrying said magazines, and each mounted to turn about a separate and independent pivotal axis located immediately below the corresponding distributor bar, means for swinging the base frames conjointly to bring one or another of the magazines into operative position, and intermediate magazine entrances carried by the base frames to conduct the matrices from the several distributors to their respective magazines, each of said entrances being separately pivoted to the corresponding base frame so as to be swung downwardly to give access to the interior parts.

3. In a typographical machine, the combination of a plurality of main character distributors arranged at different levels and each comprising a toothed bar and a distinct set of matrix conveying screws, a font separator arranged in line with the upper distributor, a plurality of superposed inclined magazines, one for each distributor, separate base frames carrying said magazines, and each mounted to turn about a separate and independent pivotal axis located immediately below the corresponding distributor bar, means for swinging the base frames conjointly to bring one or another of the magazines into operative position, and intermediate magazine entrances carried by the base frames to conduct the matrices from the several distributors to their respective magazines, each of said entrances being separately pivoted to the corresponding base frame so as to be swung downwardly to give access to the interior parts, one of the entrances leading from the uppermost distributor to the lowermost magazine, and another of the entrances leading from the lowermost distributor to the uppermost magazine.

4. In a typographical machine, the combination of two main character distributors arranged at different levels, and each comprising a toothed bar and a distinct set of matrix conveying screws, the lower distributor bar being arranged in the same vertical plane as the front conveying screws of the upper distributor bar and the rear conveying screws of the lower distributor being arranged in the same vertical plane as the upper distributor bar, a font separator arranged at the level of the upper distributor and serving to direct matrices of one font directly onto the upper distributor bar and deliver matrices of other fonts to the lower distributor, two superposed inclined magazines, one for each distributor, separate base frames carrying said magazines and each mounted to turn about a separate and independent pivotal axis located immediately below the corresponding distributor bar, means for swinging the base frames in unison to bring one or another of the magazines into operative position, and intermediate magazine entrances for conducting matrices from the distributors to the respective magazines, each of said entrances being separately pivoted to the corresponding base frame so as to be swung downwardly and rearwardly to give access to the interior parts.

5. In a typographical machine, the combination of a plurality of fixed main character distributors arranged at different levels and each presenting a vertically disposed toothed bar and a distinct set of matrix conveying screws, a font separator arranged in line with the upper distributor, a plurality of

superposed inclined magazines arranged in constant operative relation to the fixed distributors, and a plurality of intermediate separately pivoted magazine entrances for conducting the matrices from the respective distributors to the magazines, one of said entrances being arranged to connect the upper magazine to the lower distributor and the other arranged to connect the lower magazine with the upper distributor, for the purpose described.

6. In a typographical machine, the combination of two fixed main character distributors arranged at different levels and each presenting a vertically disposed toothed bar and a distinct set of matrix conveying screws, two superposed inclined magazines arranged in constant operative relation to the distributors, a plurality of intermediate separately pivoted magazine entrances connecting the magazines with the respective distributors, a bridge for separating the matrices according to font at the upper distributor level, and a fixed chute associated with the bridge for conducting the matrices of certain fonts to the lower distributor, the entrance for the lower magazine being connected to the upper distributor and the entrance for the upper magazine being connected to the lower distributor, for the purpose described.

7. In a typographical machine, the combination of two main character distributors arranged at different levels, two superposed inclined magazines arranged in operative relation thereto, intermediate pivoted magazine entrances connecting the upper and lower distributors with the lower and upper magazines, respectively, a font selecting bridge disposed at the level of the upper distributor, and two pivoted base frames carrying the magazines and their respective entrances, said base frames having their pivoted axes so located that they may be swung upwardly and downwardly to interchange the magazines without disturbing the connection of the magazine entrances with the corresponding distributors.

8. In a typographical machine, the combination of two main character distributors arranged at different levels and offset slightly from vertical alinement with each other, two superposed inclined magazines arranged in operative relation to the distributors, intermediate magazine entrances connecting the distributors with their respective magazines, a font selecting bridge arranged at the level and in the vertical plane of the upper distributor, a curved chute for receiving matrices from the selecting bridge and conducting them to the lower distributor, and an independently mounted matrix guiding plate associated with the chute and sloping downwardly toward the lower distributor.

9. In a typographical machine, the com-

- bination of two main character distributors arranged at different levels and offset slightly from vertical alinement with each other, two superposed inclined magazines 5 arranged in operative relation to the distributors, intermediate magazine entrances connecting the distributors with their respective magazines, a font selecting bridge arranged at the level and in the vertical 10 plane of the upper distributor, a curved chute for receiving matrices from the selecting bridge and conducting them to the lower distributor, and a matrix guiding plate associated with the chute and sloping 15 downwardly toward the lower distributor, said guiding plate being hinged at a point located above the upper distributor so as to be swingable rearwardly and upwardly to give access to the parts.
- 20 10. In a typographical machine, the combination of two main character distributors arranged at different levels and each comprising a toothed bar and a distinct set of matrix conveying screws, a distributor box 25 arranged at the level of the upper distributor for feeding matrices, one at a time, thereto, a font separator arranged between the distributor box and the upper distributor and
- serving to direct matrices of one font onto the upper distributor bar and to deliver 30 matrices of other fonts to the lower distributor, two superposed inclined magazines, one for each distributor, separate base frames carrying said magazines and each mounted to turn about a separate and independent pivotal axis located immediately 35 below the corresponding distributor bar, the pivotal axis of one base frame being constituted by a pair of supporting arms rising therefrom and hinged to the machine frame 40 at opposite sides of the magazine with one of the supporting arms below the font selecting bridge, means for swinging the base frames to bring one or another of the magazines into operative position, and intermediate magazine entrances also carried by the base frames to conduct the matrices from the distributors to the respective magazines, each of said entrances being separately pivoted to the corresponding base frame so as to 45 be swung downwardly and rearwardly to give access to the interior parts.

In testimony whereof, I have affixed my signature hereto.

DAVID S. KENNEDY.
